GEORGE W. NEILL, OF BOSTON, MASSACHUSETTS, ASSIGNOR TO
CHICKERING AND SONS, OF SAME PLACE.

Letters Patent No. 88,729, dated April 6, 1869.

IMPROVEMENT IN PIANO-FORTE FRAMES.

The Schedule referred to in these Letters Patent and making part of the same.

To all persons to whom these presents may come:

Be it known that I, GEORGE W. NEILL, of Boston, in the county of Suffolk, and State of Massachusetts, have invented a new and useful Improvement in Piano-Fortes; and I do hereby declare the same to be fully described in the following specification, and represented in the accompanying drawings, of which—

Figure 1 is a front elevation;

Figure 2, an end view;

Figure 3, an oblique and transverse section; and

Figure 4, a horizontal section of the wooden frame, and the metallic string-frame of a piano-forte, as provided with my invention.

The purpose of the invention is to strengthen the string-frame, so as to prevent it from being bent or twisted out of its normal condition by the strain of the strings.

The metallic string-frame, to which my invention is applied, is somewhat analogous to that represented in Letters Patent No. 79,591, granted July 7, 1868, to me.

The metallic string-frame, like that shown in such patent, is composed of a metallic frame, A, and a flanged plate, D, they being applied to a wooden back frame B.

The said frame A is to be arranged between the back frame and the sounding-board, the latter not being represented in the drawings.

The metallic frame, although having a series of oblique braces, or bars c c, has no bars to extend between the strings.

In carrying out my present invention, I apply and fix to the rear side or part of the wooden back frame B, a series of auxiliary oblique chords, or brace-bars, E E, &c., there being one of them disposed directly in rear of and parallel with each of the brace-bars c c, of the string-frame.

Each of the bars E is to be bolted, or otherwise fastened to the back frame B, and besides is to be formed, near its opposite ends, with shoulders, or abut-

ments a a, for projections b b, extended from the following brace-bar c, to rest against.

There about, against the two projections b b, the ends of an arched bar, F, which, at its crown, rests against the bar c, and on a post, or cylinder G, which is interposed between the chord-bar E and the arched bar F.

A screw-bolt, d, goes through bars c F E, and the piece G, there being a nut, g, screwed on such bolt, so as to effectually hold the said bars c, E, and F, and the piece G together.

The ends of the arched bar abut against the projections b b, of the main brace-bar.

Screw-bolts h h also go through the bars c and E, and the projections b b, and receive nuts, as shown at i i.

When each of the oblique braces c, of the string-frame, is thus supported, or provided with a truss, composed of the projections b b, the arched bar, auxiliary brace-bar, its abutments, and the connection-bolts, and the middle post or centre-piece, as described, not only will the string-frame be greatly strengthened, but the strengthening parts will be enabled to perform their functions without any injurious strain on the back frame.

What, therefore, I claim as my invention, is—

The combination and arrangement of the projections b b, the arch-bar F, the auxiliary brace-bar, and its abutments on the same, and the central post G, with each of the oblique brace-bars c, of the metallic string-frame, the whole being united by screw-bolts and nuts, as set forth.

Also, fastening each of the auxiliary brace-bars to the back frame, when such bar is provided with abutments, and combined with the two projections b b, an arch-bar, F, and the string-frame brace-bar c, connected together, and arranged as specified.

GEO. W. NEILL.
